UNITED STATES PATENT OFFICE.

MICHAEL HENRY REAP AND JAMES R. FLEMING, OF SCRANTON, PENNSYLVANIA.

COAL-SEPARATOR.

1,283,896.

Specification of Letters Patent.

Patented Nov. 5, 1918.

Application filed May 25, 1918. Serial No. 236,534.

To all whom it may concern:

Be it known that we, MICHAEL H. REAP and JAMES R. FLEMING, both citizens of the United States, and residents of Scranton, in 5 the county of Lackawanna and State of Pennsylvania, have invented a new and Improved Coal-Separator, of which the following is a full, clear, and exact description.

Among the principal objects which the 10 present invention has in view are: to increase the capacity of separators of the character herein disclosed; to support the base mineral and coal without congesting the mineral delivery; and to simplify the construction of the separator.

Drawings.

Figure 1 is a side elevation of a separator constructed and arranged in accordance with 20 the present invention;

Fig. 2 is a detail view showing a side elevation of the separator mast.

Description.

25 Heretofore separators have been employed wherein spiral runways have been used, the pitch of said runways being such as to impart a centrifugal movement to the coal and product associated therewith during the descent thereof in said separator. These runways have been so constructed that the lighter particles were crowded outward to overflow the edges of certain of the runways, to be received by certain other runways for delivery. The heavier particles have in the older constructions been guided by the original runways for delivery to a special destination. Difficulties have arisen owing to the fact that the runways have been congested at the lower end thereof and the proper distribution in delivery has been interfered with.

To avoid the objections recited and to attain the objects above stated, the present invention consists in providing a tubular mast 7, upon which are mounted inclined spiral flights 8, 9 and 10, the last mentioned flight being extended beyond the first two mentioned flights and built up to arrest any particles thrown from the said first two men-

tioned flights. The arrangement of these flights is not new.

The mast 7 is furnished at intervals with elongated perforations 11 and 12. The perforations 11 and 12 are disposed adjacent 55 the inner edges of the flights 8 and 9, respectively, and are large enough to form passages for the broken stone or base mineral which delivers to the lower edge of the said flights as the mixed material is allowed to 60 run down the spiral flights.

During the passage of the mixed material down the flights 8 and 9, the lighter particles, such as coal and bone, are carried to the edges of the flights 8 and 9 and crowded 65 thereover, passing into the flight 10. With greater or lesser rapidity, the mixed materials are separated or graduated, the heavier substances, such as the stone or base mineral, sinking to the lower edge of the 70 inclined flights, while the coal and bone are floated thereby toward the upper edge of said flights. The base mineral being thus carried to the lower and inner edge of the flights 8 and 9, the speed thereof is pro- 75 portionately retarded by the diminished length of the path of the spiral. The quieting of the speed of the stone permits the same to seek the perforations 11 and 12, to be carried therethrough to the interior of 80 the mast 7.

The stone thus delivered to the interior of the tubular mast 7 falls upon the curved end 13 of the delivery chute 14 provided for the base mineral. The coal is delivered 85 from the lower end of the flight 10, as in the usual separators. Separating rods and deflectors are provided at the delivery end of the flight 10 for separating the bone and coal. These devices are not shown in the 90 present drawings, it being considered expedient to omit the showing for the reason that they are not germane to the present invention.

It is obvious that by eliminating the stone 95 or base mineral during the travel of the mixed material down the separator, the capacity of the separator is augmented by relieving the overcrowding of the materials on the various flights. It is also obvious 100

that the separation of the materials is more efficiently carried out when the elimination of the two materials is being effected at the opposite ends of what might be termed the 5 specific gravity stratification.

Claim.

The combination of a spiral separator having a plurality of inclined spiral flights;

and a hollow tubular supporting mast for 10 the same, said mast being provided with a series of openings adjacent the lower inner edges of said flights for extracting the base mineral from the mixed materials traveling over said flights.
